EPHRAIM ELLIOTT AND CHARLES E. NEWTON, OF LOWELL, MASSACHUSETTS.

Letters Patent No. 73,787, dated January 28, 1868.

IMPROVEMENT IN ARTIFICIAL LEGS.

The Schedule referred to in these Letters Patent and making part of the same.

TO ALL WHOM IT MAY CONCERN:

Be it known that we, EPHRAIM ELLIOTT and CHARLES E. NEWTON, both of Lowell, in the county of Middlesex, and State of Massachusetts, have invented new and useful Improvements in Artificial Legs; and we do hereby declare that the following is a full and exact description thereof, reference being had to the accompanying drawings, and to the letters of reference marked thereon.

The nature of our invention consists in providing an artificial leg, its frame being made of straight beams of metal, formed of the required size and shape, and its entire mechanism enclosed within a case of cloth, leather, or flesh-rubber. It also relates to the self-adjusting sockets, and the extensions applied to the upper and lower sockets, whereby one socket may be extended in position without interfering with the other. It further relates to the device for contracting and extending the artificial tendons, which give the required motion to the ankle and knee-joints, the object of this invention being to furnish an artificial leg made entire of metal, thus producing a lighter, durable, and cheaper leg, and one that will be worn with more ease by the user.

To enable others skilled in the art to make and use our invention, we will proceed to describe its construction and operation.

Figure 1 represents a side elevation of our improved artificial leg.

Figure 2 represents a front elevation of the same.

Similar letters in the different figures indicate corresponding parts.

We construct the frame of our improved artificial leg of two straight side beams, *a a*, extending from and connecting with the ankle-joint, thus forming a part of the same, to the thigh. These beams *a a* are connected by the bands *b b'*, *c c'*, and *d*, the bands *b b'* and *c c'* forming the upper and lower cases or sockets for the reception of the self-adjusting sockets *e* and *e'*. These sockets *e* and *e'* are formed and made of wood, leather, or raw hide, to suit the wants of the wearer, and are attached to the bands *b b'* and *c c'* by suitable springs, *f f'*. Between the upper and lower sockets, *b b' c c'*, and located on these straight side beams *a a*, is the knee-joint, which swings or hinges on the pivots *g g*, and is controlled by the double stop *h h*, as represented in fig. 1 by dotted lines. *i i* is the extension located between the knee-joint and upper socket *b b'*, on the straight side beams *a a*, whereby the same can be instantly adjusted in position. *j j* is the extension, located between the knee-joint and band *c c'*, on the straight side beams *a a*, band *c*, and the front and back beams *k k'*; the front beam *k* connecting with the band *c c'*, and extending to the band *c*, the back beam *k'* forming a stop for the ankle-joint, connecting with the band *d*, and extending to the top of the band *c*, thus forming an artificial calf to the limb. These extensions *i i* and *j j* are formed by teeth meshing into each other, and are held in their required positions by suitable screws. Between the bands *e e'* and *d*, and attached to the straight side beams *a a*, is the device which controls and gives proper amount of elasticity to the tendons *l l'*, which operate on the knee and ankle-joints. This device consists of the frame *m m*, which is secured to the rods *m' m'*, these rods being fastened to the straight side beams *a a*. Passing through and running in this frame *m m* is a pivot or shaft, on which a double drum is placed and secured, for the reception of the springs *n n'*, the tendon *l* connecting with the band *b b'* and spring *n*. On one side, and attached to this drum, is the ratchet *o*. On the other side is attached the thumb-wheel *o'*, which wheel is used, when more or less tension is desired, to give a greater or less amount of elasticity to the tendons *l l'*. The ratchet *o* is held in position by the pawl *p*, which operates on the top rod *m'*. *q* is the ankle-seat, to which is secured the artificial foot *q'*, by means of the screw *r*, which passes up through the heel of the artificial foot, and pin *r'*, passing through the instep. *l'* is the tendon, one end of which is attached to the spring *n'*, the other end fastened to the front of the ankle-seat *q*. *t* is the adjustable heel-cord, one end of which is fastened to the back beam *k'*, the other end to the top of the ankle-seat *q*, at the heel-end. Placed between the bottom of these straight beams *a a* is the block *v*, which is secured and held in position by the pivots *u u*. This block *v* is secured to the ankle-seat by the pivot *w*, thus forming the ankle-joint.

The artificial leg being thus prepared, and its several parts put together, it is then ready for use, and is secured to the person in the usual way, by a strap connecting with the band *b*, and passing over the shoulder, or in any other way, as desired.

Where the person has lost his limb between the knee and ankle, two bearings are oftentimes desired, as they enable the user to wear and use the artificial leg with more ease and comfort. By our improved artificial leg, this great advantage is gained by dispensing with the tendon *l*. Having the socket *e'* for the stump-bearing, the socket *e* for the other bearing between the knee and thigh, and by the aid of the self-adjusting sockets *e* and *e'*, the jar produced in walking is greatly lessened; and when sitting, the weight of the body being removed from the limb by the relaxation of the springs *f f'*, frees or relieves the leg and stump from the sockets *e* and *e'*, leaving the limb natural and easy, thus resting the same.

Oftentimes, in wearing these artificial legs, the stump and leg become swollen so much at times that the limb has to be removed; and, further, the stump is liable to shrink. By the use of the extensions *i i* and *j j* applied to the upper and lower sockets, *b b'* and *c c'*, the user is enabled to adjust either socket separately or collectively, as the case may require, getting the required bearing on the stump or leg.

In walking, if the user finds the toes not enough or too much elevated, by aid of the heel-cord *t* he is enabled to adjust the same, getting the required elevation. Also, if more or less tension is required to make the ankle-joint work more free, or to decrease the tension, by aid of the thumb-wheel *o'*, and operating the same, he is enabled to adjust the tension to suit.

When the limb is lost, and off above the knee, the socket *e'* and extension *j j* are dispensed with, and a suitable knee-pan is provided, and secured to the straight side beams *a a*, and the tendon *l* is retained, which aids the user, in walking, when the leg is bent at the knee-joint, to throw the foot and leg forward in position, where it is checked and controlled by the stop-motion *h h*, as seen in fig. 1 by dotted lines, the tendon *l'* elevating at the same time the foot *q q'*, until stopped by the heel-cord *t*. The tension of these tendons is regulated by aid of the thumb-wheel *o'*, and retained by aid of the pawl *p* and ratchet *o*. The sideways motion, or the turning of the foot *q q'* at the ankle-joint, is produced by the ankle-seat *q* swinging on the pivot *w*. The extension *i i* and socket *e* are operated and adjusted the same as before described.

Thus it will be seen that our artificial leg is adapted and can be applied to the unfortunate person who has lost his leg below or above the knee, making a strong, light, durable leg, easily kept in order, its artificial tendons and cords easily regulated, the joints working natural and life-like, without any sharp points exposed to endanger the wear of the user's clothes, and its entire mechanism and construction meeting the demands of the public.

What we claim as our invention, and desire to secure by Letters Patent, is—

1. We claim the self-adjusting sockets *e* and *e'*, for the purposes substantially as described and set forth.
2. We claim the extensions *i i* and *j j*, applied to the upper and lower sockets, *b b'* and *c c'*, for the purpose of adjusting the same in position, as described and fully set forth.
3. We claim an artificial leg, provided with straight side beams *a a*, bands *b b'*, *c c'*, and *d*, when arranged as herein described, and for the purpose set forth.
4. We claim the double stop *h h*, in combination with the straight side beams *a a*, for the purposes as described and set forth.
5. We claim the arrangement and combination of the thumb-wheel *o'*, ratchet *o*, pawl *p*, and frame *m m*, for the purpose substantially as described.
6. We claim the combination of the ankle-seat *q*, pivots *u u'* and *w*, block *v*, and adjustable heel-cord *t*, when arranged to operate substantially as described and set forth.

EPHRAIM ELLIOTT,
CHARLES E. NEWTON.
